PLAITING MACHINE

Sam Michlin, Brooklyn, N. Y.

Application August 20, 1949, Serial No. 111,508

4 Claims. (Cl. 223—28)

1

The present invention relates to an apparatus for plaiting sheet material.

Plaited material is used in the manufacture of dresses, dress shirt bosoms and the like. It is important that the material be plaited before being assembled into the goods in as economical manner as possible. Heretofore, in making such material it generally has been necessary to plait the material by hand, a tedious and expensive operation. Prior devices have been made to make the plaits by machine but generally have been limited to the making of a single plait. Such devices, in some cases, are adapted to be inserted in the plait and followed up with the usual hand pressing iron. Obviously, such devices would not lend themselves to the plaiting of a plurality of plaits in rolled material to be cut up in the making of dresses or other articles.

The present invention aims to overcome the foregoing difficulties and disadvantages by providing an apparatus for plaiting sheet material in which a plurality of plaits may be made simultaneously, the number of plaits being limited only by the width of the material.

Another object of the invention is to provide a plaiting apparatus which is simple and economical in manufacture, efficient in operation and durable in use.

Still another object of the invention is to provide a plaiting device which may be operated by unskilled labor.

In accordance with the invention, the foregoing objects are accomplished by an apparatus embodying a forming die into which the plait is received, a spherical form being inserted into the fold of the material to align it so that it is received by the die in the proper form.

The invention is advantageous in that the plaits may be of different sizes and may be positioned as closely together, or may be made to overlap, if desired.

Other objects and advantages of the invention will be apparent from the following description and from the accompanying drawings which show, by way of example, an embodiment of the invention.

In the drawings:

Figure 1 is a plan view of an apparatus in accordance with the invention.

Figure 2 is a vertical sectional view taken along the line 2—2 of Figure 1.

Figure 3 is a vertical sectional view taken along the line 3—3 of Figure 1.

Figure 4 is an enlarged view of a single unit of the apparatus for producing a single plait.

Figure 5 is a bottom view corresponding to Figure 4.

Figure 6 is a vertical sectional view taken along the line 6—6 of Figure 4.

Figure 7 is a vertical sectional view taken along the line 7—7 of Figure 6.

Referring to the drawings, there is shown a

2

plaiting apparatus 1 in accordance with the invention comprising a supporting frame 2 having at one end a roller 5 supporting material 6 to be plaited, the frame having at its other end a pair of mangle rollers 7 and 9.

The supporting frame 2 may be of any suitable design and includes a flat table 10 which is preferably heated as by steam pipes such as used in clothes pressing machines. At the end of the table 10 is a guiding trough 11 to direct the material 6 between the mangle rollers 7 and 9 which are heated in any suitable manner, preferably by steam, and provided with screw adjusting means 12 acting through a spring 14 to adjustably and resiliently urge the mangle rollers together with a desired pressure. The roller 5 is pivotally mounted as indicated at 15 and carries on its surface the material 6 which has previously had one or more tucks sewn along its length for the plaits.

A plaiting device or plait former 16 may be fixedly attached to the supporting frame but preferably is unattached as shown in Figure 1 for hand manipulation as the material is fed over the supporting table 10. The plaiting device 16 comprises a plurality of plaiting units 17, each of which may be similarly constructed as shown in Figures 4 through 7 although each may be made in different sizes.

A supporting and manipulation means 19 for the plaiting device 16 may be made of wood or other suitable material and has attached on its front surface a pair of guide members 20 and 21 positioned facing each other and spaced at a somewhat greater amount than the width of the plait. The guide members 20 and 21 have their outer ends 22 and 24 flared away from each other, and their inner ends 25 and 26 are turned outwardly and apertured to receive retaining screws 27 for attachment to the supporting member 19.

A spherical member 30 is provided to open a tuck 31 sewn in the material for the plait. The spherical member 30 may be of any suitable material and, preferably, is made with a polished surface so as to reduce the friction between it and the inner surface of the tuck, and is of a size so that it snugly fits in the tuck, its purpose being to straighten out the material prior to its passage into an internal die to form the plait.

The die 32 is formed of any suitable material such as sheet metal or plastic or it may be molded or cast of any suitable material to provide an internal die surface as shown in Figure 7. The die 32 as illustrated is shaped of sheet material starting from a flat surface 34 by turning its sides 35 and 36 back over the flat portion 34 leaving a space 37 between the two surfaces and again bending the outer edges of the strip outwardly and back over the surfaces 35 and 36 to form outer edges 39 and 40 providing a base surface adapted to override the surface of the

material 6. A space 41 is left between the surfaces 39 and 40 to receive the stitched surface of the tuck which is received in the space 37. Spacing members 42 and 44 are used to hold the surfaces 39 and 40 away from the supporting member 19, the formed die being secured in position against the supporting member 19 by screws 45 extending through apertures in the surfaces 39 and 40 into the supporting member 19.

As may be seen in Figures 4 through 6, the 10 internal die 32 has a length approximately equal to the width of the supporting member 19, its leading edge being turned upwardly as indicated at 46 to provide a flared end to receive the material to be plaited. The base surfaces 39 and 15 40 are extended ahead of the frame 19 to provide a leading edge to facilitate threading the tuck into the passage 41 and to start the material through the plaiting device. The leading 20 ends of the surfaces 39 and 40 may be cut at an angle as indicated at 47 and 49.

It is obvious that the plaits may be made of different sizes provided the spherical member 30 is made of a size to snugly fit within the tuck and the die 32 is made large enough to receive and form the plait.

In using the device, the material 6 to be plaited is placed on the roller 5 having preformed tucks 31 on its upper surface along its length at the desired positions for the plaits, the tucks being 30 of the desired size for the plait. Spherical members 30 are inserted in the tuck in the edge of the material and the material then is threaded through the internal die 32. Steam is applied to the steam table 10 and to the mangles 7 and 9. As the material is pulled through the mangle rollers 7 and 9 it is drawn through the internal die 32, the spherical members 16 straightening the tuck so that it enters the internal die 32 conforming to the internal surface thereof. As the material has been steamed it is quite flexible and readily assumes the desired shape of the plait. The movement of the material 6 through the internal die moves the spherical member 30 through the tuck. The mangles 7 and 8 heat and dry the material 6 and set the plaits.

It is thus apparent that an apparatus for plaiting has been provided which overcomes the difficulties and disadvantages of prior devices in that the material may be cheaply and speedily processed utilizing apparatus which is simple and economical in manufacture and durable in use.

While the invention has been described and illustrated with reference to a specific embodiment thereof, it will be understood that other embodiments may be resorted to without departing from the invention. For example, while the plaiting devices have been shown as placed side by side, in alternative constructions the devices might be positioned in a staggered relationship so that plaits may be formed overlapping each other or in other desired configurations. Therefore, the form of the invention set out above should be considered as illustrative and not as limiting the scope of the following claims.

I claim:

1. A plaiting apparatus for tucked material, each tuck having an attached-together portion, comprising a plait former including a passage therethrough defined by entrance and exit ends, the entrance end of the passage expanded to receive a tuck in expanded form, the exit end

of the passage shaped to conform to the cross-sectional outline of the finished plait, the plait former passage having a longitudinally extending section of reduced diameter to guide the attached-together portion of the tuck, and a spherical member of a size to be received in the tuck for the expansion thereof, the entrance end smaller than the spherical member, the spherical member when positioned in the tuck held against the entrance end of the passage in the plait former by movement of the material through the plait former.

2. A plaiting apparatus for tucked material comprising a plait former having a passage therethrough defined by entrance and exit ends, the entrance end of the passage expanded to receive a tuck in expanded form, the exit end of the passage shaped to conform to the outline of the finished plait, heating means operatively connected to the apparatus for softening the material to be plaited, and a spherical member of a size to be received in the tuck for the expansion thereof, the spherical member when positioned in the tuck held against the entrance end of the passage in the plait former by movement of the material through the plait former, the said heated material shaped into a plait by the plait former.

3. A plaiting apparatus for tucked material comprising a plait former having a passage therethrough defined by entrance and exit ends, the entrance end flared to receive a tuck in expanded form, the exit end flattened and shaped to conform to the outline of the finished plait, steaming means operatively connected to the apparatus for softening the material to be plaited, and a spherical member having a diameter such that it fills the tuck and is movable therethrough for the expansion thereof, the spherical member when positioned in the tuck held against the entrance end of the passage in the plait former and moved through the tuck by movement of the material through the plait former, the steamed material shaped into a plait by the plait former.

4. A plaiting apparatus for tucked material comprising a plait former having a passage therethrough defined by entrance and exit ends, the entrance end flared to receive a tuck in expanded form, the exit end flattened and shaped to conform to the outline of the finished plait, steaming means operatively connected to the apparatus for softening the material to be plaited, mangle means for pressing the plaited material, and a spherical member having a diameter such that it fills the tuck and is movable therethrough for the expansion thereof, the spherical member when positioned in the tuck held against the entrance end of the passage in the plait former and moved through the tuck by movement of the material through the plait former, the steamed material shaped into a plait by the plait former and pressed by the mangle means to aid in maintaining its plaited shape.

SAM MICHLIN.
